UNITED STATES PATENT OFFICE.

WILFRED LEWIS, OF HAVERFORD, PENNSYLVANIA, ASSIGNOR TO THE TABOR MANUFACTURING COMPANY, OF PHILADELPHIA, PENNSYLVANIA, A CORPORATION OF PENNSYLVANIA.

JAR-MOLDING MACHINE.

Application filed May 17, 1922. Serial No. 561,690.

My invention relates to jar molding machines and particularly, though not in all of its features, exclusively, to the type of machine known as shockless jar molding machines. The objects of my invention are, in the first place, to provide improved means for supporting the anvil of a shockless machine on a cushion or spring of compressed air which is automatically maintained at such volume and pressure as to avoid all danger of forcing the anvil too far upward. The other object which I have in view and which, while especially adapted for use with shockless machines, can also be used with other types of machines in which the jarring table is actuated by compressed air through a cylinder and piston, is, to conduct the exhaust air through a passage formed in the anvil and connect it with a delivery port opening in the space between the anvil and the jarring table so that the constant throwing of air jets across the top of the anvil will keep it clean and prevent the collection of impacted sand and dirt on top of the anvil which is apt to occur when no means are employed to prevent it.

The nature of my improvements and the best mode in which I have planned to embody them in a machine will be best understood as described in connection with the drawings in which they are illustrated and in which

Figure 1 is a vertical sectional elevation through a shockless jarring machine embodying my improvement.

Figure 2 is a similar view on a smaller scale showing the jarring table in elevated position and the valves M⁴ and N² in the positions they occupy when the table is so positioned and

Figure 3 is an enlarged scale view of the valves M⁴ and N² and their coacting devices. In the drawing, A is a fixed cylinder; A¹, A², being stools or shoulders in the bottom of this cylinder on which the anvil rests when air is exhausted from the cylinder; B, a stuffing box at the open top of the cylinder; C, an anvil piston working in the cylinder A and, as shown, and for convenience in construction of machine, made in two parts, C and C¹, these parts being firmly secured together by any convenient mechanism. C² is a cylindrical space formed in the center of the anvil piston and closed at bottom, as shown, by a block or head indi-

cated at D and firmly secured in place to and at the bottom of cylindrical space C². E is an exhaust port leading from the cylindrical space C² through the head D and formed with a valve seat e at its top. This port E connects with exhaust passages indicated at E¹, E¹, formed in the anvil piston and connected, as shown, through passages E³ and E⁴ with an annular recess or chamber E⁵ formed on the inside of the cylindrical space C². E² is an exhaust port leading into the exhaust passages E¹ through the bottom of the anvil piston, said port being formed with a valve seat e² at its lower end. F is a hollow piston fitting and vertically movable in the cylindrical space C² and forming a tight fit therewith at its lower end through packing rings, as shown. This hollow piston is formed with ports indicated at F¹ which keep its hollow center in communication with the chamber E⁵ and is further provided with outlet ports indicated at F² which open into the space at the top of the anvil and the jarring table, and through this space exhaust to the atmosphere. G indicates the jarring table secured to the upper end of the piston F, as shown, and G¹ is the usual cushion employed between the anvil and the jarring table and constituting essentially the top of the anvil.

H is a valve casing located in the bottom of the fixed cylinder A and opening at top into this cylinder through a passage formed, as shown, in an annular gland nut H¹ having a valve seat h¹ at its lower edge. I is a hollow cylinder extending through the vertical opening in the valve casing H and formed with an annular valve I¹ adapted to seat itself on the seat h¹. The hollow cylinder I which constitutes the valve spindle is formed with a shoulder I² and provided at its top with a cylindrical nut I³ which forms an upper shoulder for the cylindrical portion I⁴ of the valve stem which extends between the shoulders I² and I³. J is a valve normally seated on the seat e² of the exhaust port E² and formed at the top of a rod J¹ which extends into the hollow valve stem I and is provided with a head J² which is movable between the stops I² and I³. K is a spring acting against the valve I, I¹, to press it upward and K¹ is a spring acting against the head J² to press in its stem J¹ and valve J upward.

L indicates a valve casing secured in the

bottom of the hollow piston F as shown, said casing being closed at top by block L¹ and opening at its lower end into the bottom of the cylindrical space C², the outlet passage 5 L² being formed with a valve seat l², as shown. M is a casing guided in the casing L and vertically movable therein, the casing M being closed at top by a cap M¹ and having at bottom a sleeve M² at the bottom of 10 which is formed a valve M⁴ adapted to seat itself at proper times on the valve seat l². M² are openings through casing M. N is a piston vertically movable in the casing M, this piston being hollow and formed with 15 the piston rod extension N¹ at the bottom of which extension is formed a valve N² adapted to seat itself on the seat e of the exhaust port E. N³, N⁴, indicate openings through the sides of the hollow piston rod N¹ and 20 N⁴ is a spring supported on the piston rod and acting against the cap N¹ of the cylindrical casing. This particular valve construction is shown simply as one well adapted 25 for its purpose and forms in itself no part of my present invention.

O indicates a conduit from the source of air under pressure; O¹ a valve in said conduit leading to a conduit section O², from which in turn leads the pipe O³ connecting, 30 as shown, with the valve casing H. At the top of the conduit section O² is a valve O⁴ through which the conduit is connected through a flexible section O⁵, and sections O⁶ and O⁷ moving with the piston F, with 35 the top of the valve casing L.

When it is desired to start the apparatus, the anvil C, it may be assumed is in its lowermost position, resting on the stools or ledges A¹ and A²; in this position the piston rod 40 J¹ is forced downward and through its head J² presses down the hollow valve stem I, maintaining the valve I¹ widely open while, of course, the valve J is firmly held against the valve seat e². The valve O¹ is then 45 opened and air under pressure admitted through conduits O² and O³ into the valve casing H from which it passes freely through the open valve port into the bottom of the cylinder A, moving upward the anvil piston 50 C which, as it moves upward, permits the upward motion of the hollow valve stem I of the valve I¹ until said valve is seated, cutting off further admission of air to the cylinder A, and it will be obvious that after 55 the closing of the valve I¹ the anvil piston C may still move farther upward for a distance corresponding to the distance between shoulders I² and I³ before the contact of head J² of the valve stem J¹ with shoulder I³ will arrest the upward motion of the valve J, after which an upward motion of the anvil piston will cause the valve J to leave its seat and permit the escape of pressure air through the port E² into the passages E¹ and thence through passages E³

and E⁴ to chamber E⁵ from which it passes through ports F¹ into hollow piston F and through ports F² to exhaust over cushion G¹. It is also obvious that the anvil piston cannot be forced farther upward by the air 70 under pressure as at the described height the port E² is always opened and the air permitted to exhaust. In moving as described the anvil C of course carries with it the hollow piston F. 75

The proper amount of air to form a resilient cushion or spring to support the anvil piston having been admitted, as described, and the anvil raised by the air to a proper height, the valve O⁴ is opened and the air 80 admitted under pressure to the valve casing L, the piston F carrying this valve casing being, of course, in its lowermost position, as shown in Fig. 1 of the drawing, with the valve N² closing the exhaust port E and the 85 valve M⁴ open, for the reason that the spring N⁴ acts to press the cylindrical casing M to its uppermost position. The air will, therefore, flow through the casing L and the port l² into the lower end of the cylindrical 90 space C² below the piston F with the result, of course, that the piston F is moved upward and while the piston F is moving upward the casing M and parts connected with it remain stationary and exhaust valve N² 95 remains seated until the valve M⁴ comes in contact with the seat l² cutting off the admission of air to the cylinder C². A further upward movement of the piston F lifts the valve N² from its seat on the exhaust 100 port and at the same time through the openings N³ permits the pressure air on the inside of the hollow valve stem and the top of the casing M to exhaust whereupon the pressure air which has entered the portion 105 of the cylinder below the piston N through openings M² formed in the wall of the cylinder M forces the valve stem N¹ rapidly upward insuring the prompt opening of the 110 exhaust port.

In Figs. 2 and 3 the jarring table is shown in its upper position, the valve M⁴ seated on port l² and valve N² slightly lifted from seat e. Immediately after the parts reach their 115 positions the pressure air in casing L entering cylinder M through ports M² forces piston N to the top of casing M so that as the table and piston F fall the air in cylindrical space C² escapes freely through port E until the parts again occupy the position shown 120 in Fig. 1.

It will readily be understood how the admission and exhaust of air under pressure to and from the cylindrical space C² causes a reciprocating movement of the jarring table 125 and of the air supported anvil and it will be obvious that in the construction shown the exhaust air is carried through the described ports and passages of the hollow piston F to the ports F² through which it passes into the 130

space between the anvil and the jarring table, constantly sweeping away any sand or dirt which may get into this space and keeping the contacting faces clean.

5 Having now described my invention, what I claim as new and desire to secure by Letters Patent, is:

1. In a jar molding machine having an anvil and a jarring table operating therewith 10 and actuated by compressed air through a cylinder and hollow piston, air exhaust passages leading from the cylinder and connected with the hollow piston and air exhaust passages leading from the hollow piston 15 directed horizontally into the space between the anvil and the jarring table.

2. In a jar molding machine an anvil having a cylindrical space formed in it together with a chamber having openings connecting 20 it with the upper portion of said cylindrical space and an exhaust passage leading from the base of the cylindrical space through the anvil to said chamber in combination with a hollow piston working in the cylindrical 25 space, a jarring table supported on said piston, said hollow piston having two sets of ports opening through its walls, one set located to register with the chamber formed on the inside of the cylindrical space and the 30 other set located to register with the space between the face of the anvil and the jarring table.

3. In a shockless jar molding machine comprising a fixed cylinder, an anvil moving 35 therein and formed with a cylindrical space within it for the jarring table piston, a jarring table piston moving in said cylinder and a jarring table supported thereon, means for admitting and exhausting air under pressure to and from the fixed cylinder and the cylindrical space, exhaust ports one leading 40 from the bottom of the cylindrical space in the anvil and the other formed in the bottom of the anvil opening into the fixed cylinder, an exhaust passage formed in the anvil into 45 which said ports open, valve mechanism carried by the jarring table piston operating to alternately admit pressure air to the cylin-

drical space in the anvil and to open the exhaust port from said cylindrical space, a 50 valve casing located in the fixed cylinder connected with a source of pressure air, said casing having a port leading into the fixed cylinder, a valve for opening and closing said port normally moved toward its seat by resilient means, means for opening said valve actuated by the downward movement of the anvil beyond a determined level, a valve normally held seated on the exhaust port in the bottom of the anvil by resilient means and 55 a stop operating to prevent the upward movement of said valve beyond a determined height so as to open the exhaust port when the anvil moves above said point.

4. In a shockless jar molding machine 60 comprising a fixed cylinder, an anvil moving therein and formed with a cylindrical space within it for the jarring table piston, a jarring table piston moving in said cylinder and a jarring table supported thereon, means 65 for admitting and exhausting air under pressure to and from the fixed cylinder and the cylindrical space, exhaust ports one leading from the bottom of the cylindrical space in the anvil and the other formed in the bottom 70 of the anvil opening into the fixed cylinder, an exhaust passage formed in the anvil into which said ports open, valve mechanism carried by the jarring table piston operating to alternately admit pressure air to the cylindrical space in the anvil and to open the exhaust port from said cylindrical space, a 75 valve casing located in the fixed cylinder connected with a source of pressure air, said casing having a port leading into the fixed cylinder, a vertically movable valve for opening and closing said port normally pressed upward to close position by resilient means, a valve opening rod longitudinally movable 80 between stops in the valve stem, resilient 85 means acting to press said rod upward and a valve on the end of said rod normally seated on the exhaust port in the bottom of the anvil.

WILFRED LEWIS.
